UNITED STATES PATENT OFFICE

FRANK WARD REILLY, OF CHATTANOOGA, TENNESSEE, ASSIGNOR TO WILLIAMSPORT WIRE ROPE COMPANY, A CORPORATION OF PENNSYLVANIA

FITTING FOR HEAVY DUTY SUSPENSION HANGERS

Application filed January 10, 1930. Serial No. 419,920.

This invention relates to a fitting for use in connecting to a span cable or the like a hanger designed for heavy duty in bridge construction, etc.

5 It is an object of the present invention to provide a fitting utilizing a saddle which extends over an extensive surface on the span cable whereby there is a low unit bearing pressure on the cable because 10 of the wide distribution of the load and whereby the bending of the cable is minimized by the creation of a wide radius of curvature.

Another object is to provide a fitting the 15 saddle portion of which is adapted to be connected to the cable at two points, thereby preventing slipping and insuring a high degree of safety.

A further object is to provide a structure 20 wherein the load sustained by the supported hanger is applied downwardly through the fitting onto the cable so that the material is placed in compression.

With the foregoing and other objects in 25 view which will appear as the description proceeds, the invention resides in the combination and arrangement of parts and in the details of construction hereinafter described and claimed, it being understood 30 that changes in the precise embodiment of the invention herein disclosed may be made within the scope of what is claimed without departing from the spirit of the invention.

In the accompanying drawings, the pre- 35 ferred form of the invention has been shown.

In said drawings,

Figure 1 is a side elevation of the fitting in engagement with a hanger and cable.

Figure 2 is a top plan view thereof.

40 Figure 3 is a section on line 3-3, Figure 2.

Figure 4 is a section on line 4-4, Figure 2.

45 Referring to the figures by characters of reference, 1 designates an elongated saddle having a central upstanding ear 2. Adjacent its ends the saddle is formed with depending lugs 3 adapted to receive the span cable A between them. The saddle is formed 50 with grooves 4 whereby it can fit snugly

against the cable A and, when clamped thereon, will be held against movement longitudinally of the cable. Each end portion of the saddle is engaged by a U-bolt 5 and these bolts have nuts 6 by means of which they can be tightened so as to bind firmly 55 against the cable A and, in turn, cause the saddle to fit tightly upon the cable.

A clevis 7 straddles the cable and the middle portion of the saddle and has eyes 60 8 at opposite sides of the ear 2. A coupling pin 9 is extended transversely through central holes in the eyes 8 and ear 2 and is held in place by any suitable means such as cotter pins 10. A hanger which can be 65 in the form of a rod 11 is suitably secured to the clevis. Where very long hangers are required, however, a cable can be attached to the clevis by any suitable means in lieu 70 of the rod 11.

By connecting the hanger as described, the load is transmitted downwardly onto the saddle through the pin and is thus distributed to the cable over an extensive area. Consequently the material is maintained under compression and the bending of the 75 cable is greatly minimized.

By utilizing a fitting of this type a standard clevis can be used as shown at 7.

One important advantage resulting from 80 the use of a fitting such as described is the fact that a bridge can be started from one end and each successive floor section can be pushed out from the flooring that has previously been suspended by the hangers. 85 After each section is brought to proper position it can be fastened by tightening the U-bolts 5.

What is claimed is:

1. A fitting of the class described includ- 90 ing an elongated saddle adapted to rest upon a span cable and having helical grooves to receive cable strands, means at the ends of the saddle for binding it upon said cable, a hanger engaging clevis suspended from the 95 saddle and straddling the cable and saddle, and a coupling pin connecting the clevis to the saddle for transmitting the weight of a load from the clevis through the saddle to the cable. 100

2. A fitting of the class described including an elongated saddle adapted to bear upon a span cable or the like and having near the ends depending lugs embracing the cable, means at the ends of the saddle for straddling said cable to bind the saddle thereto, a hanger supporting clevis adapted to straddle said cable and the saddle, and means engaging the clevis and the middle portion of the saddle for transmitting the weight of a load from the clevis through the saddle to the engaged cable.

3. The combination with a span cable or the like, of an elongated saddle having grooves for receiving portions of the cable, depending lugs adjacent the ends of the saddle for receiving the cable between them, U-bolts adjacent to the lugs for straddling the cables and binding the saddle thereto, a central ear integral with the saddle, a clevis embracing the cable and saddle and extending to opposite sides of the ear, and a coupling pin extending through the clevis and ear for transmitting the weight of a load from the clevis through the saddle to the cable.

4. A hanger fitting for use with a span cable or the like, comprising an elongated saddle having grooves for receiving portions of the cable, depending lugs adjacent the ends of the saddle for receiving the cable between them, U-bolts adjacent to the lugs for straddling the cable and binding the saddle thereto, a central ear integral with the saddle, a clevis embracing the cable and saddle and extending to opposite sides of the ear, and a coupling pin extending through the clevis and ear for transmitting the weight of a load from the clevis through the saddle to the cable.

In testimony that I claim the foregoing as my own, I have hereto affixed my signature.

FRANK WARD REILLY.
